UNITED STATES PATENT OFFICE.

ROBERT A. LYCHOU, OF CHESTER, PENNSYLVANIA.

WINDOW WASHER.

Application filed April 29, 1924. Serial No. 709,862.

To all whom it may concern:

Be it known that I, ROBERT A. LYCHOU, a citizen of the United States, residing at Chester, in the county of Delaware and 5 State of Pennsylvania, have invented new and useful Improvements in Window Washers, of which the following is a specification.

This invention relates to a window washer, 10 and more particularly to a window washing device designed principally for use in washing the windows of street-cars, railway passenger cars, and the like, and the brush is also adaptable for washing any desired 15 surface, such as the surface of the cars, building windows or the like.

An object of the invention is to provide 20 a brush as specified, of the fountain brush type, wherein the cleansing fluid, preferably water, enters the brush under pressure and 25 rotates the brush-head carrying the bristles, so as to cause a rotary movement of the bristles over the surface being washed, while at the same time, the water passes through 30 the brush upon the surface being washed, thereby permitting a thorough cleaning of 35 the surface with minimum exertion.

Another object of the invention is to provide 40 a brush structure as specified, a novel form of rotor including a plurality of blades against which the water entering the brush engages for rotating the brush-head and the blades are further shaped to direct the water to the outlet openings through the brush for 45 application to the surface being cleaned, and also to provide means for preventing the bristles of the brush being too tightly pressed against the surface being cleansed.

Other objects of the invention will appear 50 in the following detail description, and in the accompanying drawings wherein:

Figure 1 is a side elevation of the improved brush.

Figure 2 is a vertical section through the 55 brush.

Figure 3 is a cross section on the line 3—3 of Figure 2.

Figure 4 is a detail view of the inner surface of the brush-head.

Figure 5 is a detail perspective view of one of the blades of the propelling rotor.

Referring more particularly to the drawings, the improved washer or brush comprises a body shell 1 which has a boss 2 formed centrally on its rear closed side, the

outer surface of which boss is threaded and receives the internally screw-threaded nipple 3 to which the handle 4 is attached. The handle 4 may be of any approved shape or length, depending upon the use to which the 60 brush is to be put.

The body shell 1 opens outwardly at one side, and the brush-head 5 fits snugly against the edge of the body shell at its open side, as shown in Figure 2 of the drawings. A reduced portion 6 is formed on the brush-head 5 and extends into the body shell. Suitable bristles 7 are attached in any suitable manner to the brush-head 5 and are protected by an annular band 5', which may be of such size that it engages the outer bristles by friction. A propelling rotor 8 is attached to the inner surface of the brush-head 5 in any suitable manner, preferably by screws 9, and it comprises the flat blades 10 which abut the inner surface of the brush-back 5 and which have the transversely extending blades 11 along their edges. The inner ends of the blades 11 are cut free from the flat blades 10, and are bent transversely to both the blades 10 and 11, providing the inwardly inclining guide blades 12 which are arranged to direct water towards the elongated openings 13, formed through the brush-back 5. The openings 13 are spaced 70 between the flat blades 10, as clearly shown in Figure 3 of the drawings, and the water passes through these openings and the bristles 7 upon the surface being cleaned. 75 The blades or buckets may be described as 80 each including flat portions to be secured to the inner surface of the brush-head, portions deflected perpendicularly with reference to the flat portions and extending radially from the axis of rotation, and portions 85 extending in approximately the same direction as the elongated openings or ports 13 and spaced inwardly from said openings and between the latter and the axis of rotation.

The water inlet into the body shell 1 is 90 through the inlet extension 15, which projects tangentially from the perimeter of the body shell so that the water entering under pressure, will strike the blades 11 and rotate the propelling rotor 8 upon its supporting shaft 16. The rotation of the propeller 8, will rotate the brush structure, causing the brush to be rotated rapidly over the surface being washed or cleaned. It is desirable 95 to constrict the inlet into the body cas- 100

ing 1 over the supply opening to the inlet so as to increase the force of the water entering the body casing.

The shaft 16 extends axially through the 5 bosses 2 and through the brush-head 5, and this stop has a rounded surface 18 terminating a short distance inwardly of the outer ends of the bristles 7. The stop 17 is adapted to prevent the brush-head from being tightly 10 pressed against the object being washed, and consequently, to protect the bristles and ensure a thorough washing.

While in the foregoing description, the device has been mentioned as particularly 15 adaptable for washing windows, and street and railway passenger coaches, it is to be understood that it is applicable for washing any suitable surfaces, and it is to be understood that an ordinary hose of approved 20 type connected with the water supply is connected to the inlet 15, and the flexibility of the hose will permit the washer or brush to be readily moved about over the surface it is cleaning.

25 It is, to be understood, of course, that the invention may be constructed in various other manners and the parts associated in

different relations, and therefore, I do not desire to be limited in any manner, except as set forth in the claim hereunto appended. 30

What I claim is:

In a device as set forth, a body casing, a brush rotatably carried thereby and including a bristle carrying brush-head having a plurality of spaced elongated openings 35 therein, a rotor attached to the inner surface of said brush-head and positioned within said body casing, said body casing having a fluid inlet adapted to permit fluid entering the casing to engage against said rotor for 40 rotating the rotor and brush, said rotor including buckets having flat portions secured to the inner surface of the brush head, portions extending perpendicularly with reference to the flat portions and arranged 45 radially to the axis of rotation, and said perpendicular portions having their inner ends directed rearwardly to the direction of rotation and positioned inwardly of the elongated openings, whereby water engaging said 50 rotor will be deflected through said openings.

In testimony whereof I affix my signature.
ROBERT A. LYCHOU.
